H. B. Morrison.

Car-Mover

Nº 75447

Patented Mar. 10, 1868.

United States Patent Office.

H. B. MORRISON, OF LE ROY, NEW YORK.

Letters Patent No. 75,447, dated March 10, 1868.

IMPROVED CAR-MOVER.

The Schedule referred to in these Letters Patent and making part of the same.

TO ALL WHOM IT MAY CONCERN:

Be it known that I, H. B. MORRISON, of Le Roy, in the county of Genesee, and State of New York, have invented a new and improved Car-Mover; and I do hereby declare that the following is a full, clear, and exact description thereof, which will enable others skilled in the art to make and use the same, reference being had to the accompanying drawings forming part of this specification, in which—

Figure 1 is a side view of my improved car-mover, the side-wheel being removed.

Figure 2 is a detail sectional view of the same, taken through the line $x x$, fig. 1.

Figure 3 is a detail sectional view of the same, taken through the line $y y$, fig. 1.

Figure 4 is a detail sectional view of one of the adjustable pawls.

Figure 5 is a side view of the other pawl, part being broken away to show the construction.

Figure 6 is a side view of the rear driving-wheel, part being broken away to show the construction.

Figure 7 is a detail sectional view, taken through the line $z z$, fig. 1.

Figure 8 is a detail plan view, showing the collars and straps upon the shaft H.

Similar letters of reference indicate like parts.

My invention has for its object to furnish an improved machine, by means of which freight-cars may be easily moved about in the freight-house for convenience in loading or unloading them; and it consists in the construction, combination, and arrangement of the various parts of the machine, as hereinafter more fully described.

A are the sides of the frame of the machine, which are connected and secured in their proper relative positions by cross-bars, and by the axles B and C, which pass through them. In case the sides A should be made of wood, they should have metallic blocks, a' , let into them just above the said axles, to keep them from cutting into the said sides. D and E are the driving-wheels, which are placed and revolve upon the axle B and C, in a line with each other, so that they may both work upon the same rail of the track. The driving-wheels D and E are connected to each other by an endless chain, F, which works in deep recesses formed in the faces of the wheels D and E, said recesses having lugs formed upon their sides, against which the ends of the links of the chain F press to prevent the said chain from slipping. The upper edges of the said recesses are bevelled off, as shown in figs. 2 and 3, so as to enable the wheels to take a firmer hold upon the rail. The rear driving-wheel D is made longer than the forward one, and has a cog-wheel, d' , formed solidly upon or securely attached to its side, upon which the pawls take hold to operate the machine, the cogs being so formed, as shown in fig. 6, that the pawls may take hold of them to move the wheel in either direction with the same facility. G is a framework, securely attached to the sides A of the main frame of the machine, and strongly braced. The upper part of the framework G is connected together by the cross-bars or shafts H and I, and its rear part by the cross-bar or shaft J. The shafts H and I are connected to each other by a bar, having holes or eyes in its ends through which the said shafts pass, so that the pressure upon either of said shafts may be partially sustained by the other, as shown in red in fig. 1. K is the bar, by means of which the machine is connected to the car to be moved. The rear end of the bar K is bent up, or has a shoulder formed upon it, so that it may be conveniently passed above the bolster of the car. L is an arm or block, pivoted to the rear part of the bar K, near its end, which, as the said bar is passed above the bolster, strikes against the said bolster, and is turned up so as to strike against the bottom of the car and steady the car in its place. The middle and forward part of the bar K is slotted vertically, either by forming a slot in the said bar, or, which is the preferable manner, by means of a supplementary bar, k' , the ends of which are securely connected to the main bar, so as to leave a wide slot, as shown in fig. 7, the said part or bar k' having a longitudinal flange or shoulder formed upon its inner side for convenience in attaching the adjustable connecting-bar M, as shown in fig. 7, and in dotted lines in fig. 1. N is an adjustable stay-block, sliding freely along the bar K, and secured in place, when adjusted, by a set-screw, n' . O is an adjustable stay-block, sliding freely along the bar K, and secured in place, when adjusted, by the set-screw o' . P is a thumb-screw, passing through the upper end of the stay-block O, and having a plate, furnished with prongs or teeth, as shown in figs. 1 and 7, pivoted to its forward end.

When the rear end of the bar K has been arranged in place upon the bolster, the stay-block N is slipped forward against the front cross-sill of the car, and secured in place by the set-screw n' , the stay-block O is then

slipped back against the said cross-sill, and secured in place by the set-screw a' . Then, by means of the thumb-screw P and toothed plate, the said sill is securely clamped to the bar K . R is an adjustable standard, having holes formed through its upper end, so that it may be adjustably pivoted to the forward end of the bar K , as shown in fig. 1, and having a round tenon, with a screw-thread cut upon it, which enters the socket S , the lower end of which is pivoted to the short arm of the elbow-lever T . r' is a nut, working upon the screw-thread cut upon the round tenon of the standard R . U is a connecting or brace-bar, the upper end of which passes up through the forward part of the slot in the bar K , where it is adjustably secured in place by a pin passing through one or the other of the holes formed in the said bar. The lower end of the bar U is bent back, and forked, and is adjustably secured to the lower part of the connecting-bar M by a pin passing through one or the other of the holes formed in the lower part of the said bar M , in such a position that it may rest upon the bar or shaft J . V is a sliding block, sliding up and down upon the bar M , and having an arm, v' , projecting downward from its forward end.

The shaft J has a groove formed in or upon it, into which the forward edge of the bar M and the rear edge of the arm v' of the sliding block V enter to keep the bars U and M from lateral movement upon the said shaft. In attaching and detaching the bars U and M , the sliding-block V is slid up and catches in the notch m' , formed in the edge of the bar M .

When the bar K has been secured to the car, the machine is run back, and the long arm of the elbow-lever T , which is pivoted to the shaft I , is raised by means of the lever or hand-bar W . The bars M and U , and standard R , are adjusted and secured in place. Then, by lowering the long arm of the lever T , a portion of the weight of a car is thrown upon the machine, to cause the driving-wheels to take hold of the rail and draw the car forward. If not quite sufficient weight has been thrown upon the machine for this purpose, by turning up the nut r' with a wrench, the pressure or weight thrown upon the machine may be adjusted at pleasure. The forward or free end of the lever T W is secured by the spring-catch loop X to the forward part of the frame A . The socket S is kept from getting out of position by the loop Y , pivoted to the shaft H , and passing around the said socket. A^1 is a pawl, which is placed in a socket, B' , and is held down, so as to take hold of the cogs of the cog-wheel d' , by a coiled wire spring, C' , as shown in fig. 4.

To the upper end of the pawl A^1 is attached a short handle, a^2 , by means of which the pawl may be adjusted or reversed, so as to move the machine forward or backward, as desired, the pawl being held in place by the handle a^2 entering notches formed in the upper end of the socket B' . The socket B' is secured to the bar D' , the lower end of which rides upon the axle B . E' is a slide, adjustably secured to the bar D' by a set-screw. F' is a connecting-bar, the rear end of which is pivoted to the slide E' , and its forward end is pivoted to the short arm of the elbow-lever G' , which is pivoted to the shaft H . H' is the forward pawl, which is placed in a socket in the end of the arm I' , where it is held in place by the spring J' . The arm I' is pivoted to the bar K' , and the arm and pawl are held forward against the cog-wheel d' by the coiled spring L' pressing against the arm M' secured to the bar K' .

The pawl H' is held away from the cog-wheel d' , while the machine is being drawn from place to place, by the sliding catch N' , which is placed upon the bar K' , and is slid up into a notch formed upon the under side of the arm I' . The rear end of the bar K' rides upon the axle B , and to its forward end is adjustably pivoted the lower end of the connecting-bar O' , the upper end of which is pivoted to a slide, P' , adjustably secured to the long arm of the elbow-lever G' by a set-screw. The elbow-lever G' is pivoted to the shaft H , and is operated by the lever or hand-bar R' , attached to its long arm.

By operating the lever G' by means of the bar R' , the pawls A^1 and H' are made to act alternately upon the cog-wheel d' , drawing the car forward, and by reversing the pawls A^1 and H' , by means of the handles a^2 and h' attached to their upper ends, the same movements of the lever G' will push the car backward. By adjusting the slides E' and P' , the same movements of the lever G' will operate the machine with increased power or increased velocity, as may be desired. S' is a platform, formed upon or attached to the forward end of the frame A , upon which the operator stands when working the lever G' R' , so that his weight may cause the frame A to act as a lever in pressing down the forward driving-wheel, and causing it to take hold of the rail. T' is a bar, sliding in keepers upon the side A of the frame, and which is held in place by the said keepers entering notches in the edge of the said bar. The object of this bar is to hold the machine in a horizontal position while attaching it to the car. U' is a side-wheel, of a little less diameter than the driving-wheel D attached to the projecting end of the axle B , for convenience in moving the machine from one place to another.

A^2 are stays, swelled upon the shaft H , so as to fit tightly, and extending outward, so as to serve as stays and guides to the socket S , which passes in between them when the weight of the freight-car is being thrown upon the car-mover, said stays preventing the said socket from tipping over sideways, and also steadyng the car-mover when upon the track, and moving the car.

The various parts and pieces upon the shafts or bars H and I are kept in their proper relative positions by the tubular washers or ferrules B^2 , placed upon the said shafts or bars between the said parts for that purpose, as shown in the drawings.

What I claim as new, and desire to secure by Letters Patent, is—

1. In a car-mover, constructed as described, the two driving-wheels D and E , placed in line with each other, so as to run upon the same rail of the track, and connected to each other with an endless chain F , substantially as herein shown and described, and for the purpose set forth.
2. The combination of a side-wheel, U' , with the projecting end of the axle B of the car-mover, substantially as herein shown and described, and for the purpose set forth.
3. The driving-wheels D and E , constructed with grooves of peculiar shape for the reception of the endless chain F , and to enable them to hug the rail more closely, substantially as herein shown and described.

4. The combination of the elbow-lever G' R', bars F' D' and O' K', and pawls A' and H' with each other, and with the cog-wheel d', formed upon or attached to the driving-wheel D, substantially as herein shown and described, for the purpose of operating the machine.

5. The combination of the adjustable slide E' with the bars F' and D', substantially as herein shown and described, and for the purpose set forth.

6. The combination of the adjustable slide P' with the lever G' and bar O', substantially as herein shown and described, and for the purpose set forth.

7. The combination of the reversible pawl A', having a handle, a², attached to its upper end, coiled spring C', with the socket B' and cog-wheel d', substantially as herein shown and described, and for the purpose set forth.

8. The combination of the pawl H', having a handle h' attached to its upper end, spring J', arm M', coiled spring L', and socket-arm I', with each other and with the cog-wheel d' and bar K', substantially as herein shown and described, and for the purpose set forth.

9. The combination of the bar K, slide-blocks N and O, screw P, adjustable bars M U, slide V, adjustable standard R, and pivoted socket S, with each other and with the elbow-lever T W and frame G, substantially as herein shown and described, and for the purpose set forth.

10. The combination of the slide-bar T' with the frame A of the machine, substantially as herein shown and described, and for the purpose set forth.

11. The combination of the guide-stays A² with the shaft H, ferrules B², and sockets S, substantially as herein shown and described, and for the purpose set forth.

The above specification of my invention signed by me, this 11th day of June, 1867.

H. B. MORRISON.
